UNITED STATES PATENT OFFICE.

GEORGE M. HUBBARD, OF NEW HAVEN, CONNECTICUT, ASSIGNOR TO W.
AND E. T. FITCH, OF SAME PLACE.

WHIP-SOCKET.

SPECIFICATION forming part of Letters Patent No. 335,524, dated February 2, 1886.

Application filed November 9, 1885. Serial No. 182,222. (No model.)

To all whom it may concern:

Be it known that I, GEORGE M. HUBBARD, of New Haven, in the county of New Haven and State of Connecticut, have invented a new 5 Improvement in Whip-Sockets; and I do hereby declare the following, when taken in connection with accompanying drawings, and the letters of reference marked thereon, to be a full, clear, and exact description of the 10 same, and which said drawings constitute part of this specification, and represent, in—

Figure 1, a front view; Fig. 2, a side view; Fig. 3, a vertical central section on line x x ; Fig. 4, an inside view of the principal part, 15 the two other parts detached; Fig. 5, an inside view of the two other parts detached.

This invention relates to an improvement in whip-sockets, and particularly that class which are vertically divided, and the parts 20 hinged together, so as to automatically grasp the whip-stock.

The object of this invention is to produce a socket which may be easily cast, and one which requires very little labor to complete it; 25 and it consists in the construction, as herein-after described, and particularly recited in the claims.

The socket is divided vertically.

A represents one half of the socket, adapted 30 to be secured to a vehicle, and constructed with a notch, a , in both edges near its center, and with a lug, b , on both sides below the said notches, and also with an ear, d , at its lower end.

B is the upper part of the other half of the 35 socket, and corresponds to the upper portion of the half A. Its lower sides are extended downward and outward, projecting over the sides of the part A, beyond the notches a , and 40 are provided with inwardly-projecting trunnions e , adapted to set into the said notches a , and is also constructed with a spring-seat, f , on its front above the trunnions.

C is the lower portion of the second half, 45 and corresponds to the lower portion of the part A, and is constructed with an ear at its lower end corresponding to the ear d in the part A. The two parts are secured together by a rivet through the said ears. On each side

of the said part C, near the top, is a hook, g , 50 adapted to engage the lugs b . The edges at the upper ends are extended upward over the notches a and trunnions e therein, so as to hold the said trunnions in position. Below the upper edge of the part C is an opening, h , and 55 on the front, at the bottom of the said opening, is a spring-seat, i , corresponding to the seat f on the part B.

D is a flat spring, taking a bearing at one end in the seat f , extends downward inside the part 60 C, out through the opening h and onto the seat i . As the seat f is above the trunnions e , the tendency of the spring is to force the upper end of the part B against the part A, but yield to allow the whip to be introduced, and when 65 so introduced will grasp the whip-stock and prevent its accidental displacement.

To prevent the possible escape of the spring, the seats are each constructed with a bridge, 70 k , beneath which the end of the spring enters, and so that the ends of the spring will be substantially inclosed by the bridge.

The best method for constructing the bridge is to cast the parts with an opening, m , at the 75 end of the seat, and directly beneath the bridge, as seen in Fig. 3, and so that the bridge may be formed in the process of casting; but the bridge may be a bar brazed or soldered over the seat.

I am aware that whip-sockets have been 80 made in parts, the divisions being vertical and central, the parts hinged together with springs applied to force the parts into grasping position upon the whip, and yield for the introduction or removal of the whip; and I am also 85 aware that such sockets have been composed of three parts, one part forming one full half-length of the socket, the other two parts forming, respectively, the upper and lower half of the socket, the lower half fixed and the upper 90 half hinged, and provided with a spring. I therefore do not wish to be understood as claiming, broadly, such construction, the essential features of my invention being the peculiar construction of connecting the hinging 95 devices between the parts, and of the spring-seats, as particularly herein-after pointed out.

I claim—

1. The herein-described whip-socket, consisting of the part A, forming one vertical half of the socket, and constructed with a notch, *a*, in each edge, and with a lug, *b*, on 5 each side below the said notches, combined with the part B, forming the upper portion of the other half, constructed with trunnions *c*, set into the notches *a*, and the part C, forming the lower portion of said other half secured 10 to the part A, and constructed with a hook, *d*, on each side, to engage the lugs *b*, its upper sides extended over the notches *a*, and the trunnions therein, and the spring D, arranged to bear the part B against the part A, but

yield to allow the introduction of a whip, substantially as described. 15

2. In a whip-socket divided vertically, the parts adapted to swing the one from the other, said swinging part constructed with a seat to receive the spring and with a bridge over said 20 seat, combined with a spring, its working end resting on said seat and extending beneath said bridge, substantially as described.

GEORGE M. HUBBARD.
